UNITED STATES PATENT OFFICE

JOHN F. RAKES, OF GREENUP, KENTUCKY.

COMBINED LATHE AND DRILLING-MACHINE.

SPECIFICATION forming part of Letters Patent No. 251,945, dated January 3, 1882.

Application filed March 21, 1881. (Model.)

To all whom it may concern:

Be it known that I, JOHN F. RAKES, of Greenup, in the county of Greenup and State of Kentucky, have invented a new and Improved Combined Lathe and Drilling-Machine, of which the following is a full, clear, and exact description.

My invention consists in a novel construction, arrangement, and combination of devices whereby a reciprocating drilling-machine is produced and provision is made for converting the frame of the drilling-machine into the frame of a lathe, and for driving the lathe by the wheel used for operating the drill, as hereinafter more particularly described.

In the accompanying drawings, Figure 1 is a side view of an apparatus embodying my improvements. Fig. 2 is a front view of the same, partly in section. Fig. 3 is a horizontal section taken in the line *xx* of Fig. 1. Fig. 4 is a horizontal section taken in the line *yy* of Fig. 1. Fig. 5 is a horizontal section in the line *zz* of Fig. 1. Fig. 6 is a detail view. Fig. 7 is a horizontal section taken in the line *ww* of Fig. 1.

Similar letters of reference indicate corresponding parts.

A represents a frame or standard, made preferably of cast-iron, and provided with three legs, B B² B². The leg B is inclined at an angle of about forty-five degrees, and is permanently attached to the standard A. The two legs B² are connected by a brace, b, so as to resemble the letter A, and are provided with a screw-rod, b², and hand-nut b³ above the brace b, for clamping the upper ends to the frame or standard A.

In the upper portion of the standard A there are two arms, a a, in which works a vertical shaft, C, the lower end of which is provided with a socket and serves as a drill-holder. The upper portion of the shaft C carries a fly-wheel, C², provided with counterbalance-weights c², which may be removed when desired.

To the shaft C, below the fly-wheel, is attached a clutch, composed of two parts, D D². The part D is attached firmly to the shaft, and is concave. The part D² is loose on the shaft, and is convex, and works in the concave portion of the part D, and it is provided with two

frictional retarding-dogs, which engage with said concave part.

To the part D² is attached one end of a spring, E, which is coiled several times around said part D², and has its other end attached to the standard A. Below this spring is attached one end of a rope or cord, E², which is wound around the part D² in an opposite direction from the coil of the spring, and then passes over a pulley, e, and down to a treadle, 60 e², pivoted to the leg B. When the treadle is pressed down the unwinding of the rope or cord turns the shaft C in one direction, so as to rotate the bit or drill carried by the lower end of said shaft and winds up the spring E. 65 When the pressure on the treadle is removed the unwinding of the spring moves the loose part D² of the clutch in the opposite direction, and the shaft C and part D remain stationary, while the pawls d slip around the inner surface of the part D until the first position is attained, and then they again engage with said surface, and the first motion is repeated. By this means a reciprocating rotary motion is imparted to the part D² and an intermittent 70 motion in one direction to the part D and the shaft C. 75

In the lower portion of the frame or standard A there are two arms, a² a², in which a screw, G, works loosely, and carries at its upper end a feed-table, f. On the screw G, between the arms, is a hand-wheel, g, by turning which the feed-table is raised or lowered, as desired. The table f is prevented from turning by means of a notch engaging with a rib 80 on the standard A. 85

Pivoted to the standard, near the lower arm, is a lever, h, which is curved downward under the hub of the wheel g, so as to be used as a cam. When the feed-table is at rest the hub 90 of the wheel g rests on the lower arm a². When the table contains work to be drilled or bored it is fed up to the drill or bit by raising the lever h, so as to lift the wheel g, and with it the screw and table. 95

The standard A is formed with a web, v, extending rearward from end to end. The A-shaped leg-frame B² is attached to the lower end of the standard by clamping the lower end of said web between the upper ends of said legs 100

by means of the hand-nut b^3 on the screw-rod b^2 , as before described. When it is desired to use the standard A as a frame for a lathe the legs B^2 are removed from the lower end and placed at the opposite end, which is provided, near the corner thereof, with a notch, n , and a hook or projection, p . The legs are inclined outward from the frame, which then lies horizontally, and the notch n rests on the rod b^2 , and the hook or projection p lies between the upper ends of the legs, which are then clamped, as before described.

The lathe-heads are carried by a bar, J, at the ends of which are arms i i , provided with notches at their ends, which engage with the web v , as shown in Fig. 1. This lathe attachment may be readily placed in position and removed, and it may also be used when the standard is in an upright position, in which case the bar J is provided with a leg, J^2 . The lathe is driven by a band, l , from the fly-wheel C^2 to a pulley on the fixed head K. When the machine is in an upright position the treadle c^2 is arranged as shown in Figs. 1 and 2. When used in a horizontal position the treadle is arranged at about ninety degrees from the position shown in said figures, so as to bring its free end nearly under the pulley e .

The movable head K^2 is arranged to slide on the bar J and to be held in place by a wedge or key in the usual or any suitable manner. It is provided with a feeding device consisting of a plate, M, carried by a rod or bar, m , working in lugs or arms on the head, and a curved lever, R, arranged and operating in a similar manner to the feeding device above described. By this means provision is made for using the lathe attachment for drilling and boring purposes.

Having thus described my invention, I claim

as new and desire to secure by Letters Patent—

1. The metallic frame or standard A, formed with the web v and the arms a a and a^2 a^2 in one piece with said standard, as shown and described, for the purposes specified. 45

2. The combination, with the frame or standard A and arms a a , of the vertical shaft and drill-holder C and the fly-wheel C^2 , provided with removable counterbalance-weights c^2 , arranged as herein shown and described. 50

3. The combination, with the frame A and the shaft C, of the clutch D D^2 , dogs d d , spring E, and rope or cord E ^{2} , as shown and described, for the purpose specified.

4. The combination, with the frame A, shaft C, and clutch D D^2 , of the rope or cord E ^{2} , pulley e, treadle e^2 , and diagonally-inclined rear leg, B, when arranged and operating as herein shown and described. 55

5. The removable and adjustable leg-frame, 60 consisting of the legs B^2 B^2 , brace b, screw rod or bolt b^2 , and hand-nut b^3 , in combination with the frame or standard A, provided with the web v , notch n , and hook or projection p , as shown and described, for the purpose specified. 65

6. The combination, with the frame A and arms a^2 a^2 , of the feeding device consisting of the table f, screw G, hand-wheel g, and curved lever h, arranged and operating as shown and described, for the purpose specified. 70

7. The combination, with the frame or standard A, of the lathe attachment consisting of the bar J, provided with the notched or forked arms i i and carrying the lathe-heads K K^2 , as herein shown and described.

JOHN F. RAKES.
